SOUND ABSORBING CABINET FOR TABLE MODEL BUSINESS MACHINES

George A. Reed and Dexter Rosen, Williamsville, N.Y.,
assignors to Gates Acoustinet, Inc., Tonawanda, N.Y.,
a corporation of New York

Filed May 19, 1960, Ser. No. 60,656

Term of patent 3½ years

(Cl. D64—11)

Fig. 1

Fig. 2.

Fig. 3.

Fig. 4.

Fig. 5.

Fig. 6.

Fig. 1 is a front perspective view of a sound absorbing cabinet for table model business machines embodying our new design, the machine shown therein in broken lines being for illustrative purposes only;

Fig. 2 is a front elevational view thereof as it appears with the machine removed therefrom;

Fig. 3 is a rear elevational view thereof;

Fig. 4 is a side elevational view thereof, viewed from the right hand side of Fig. 2, the opposite side elevational view being substantially the same;

Fig. 5 is a top plan view thereof;

Fig. 6 is a bottom plan view thereof.

We claim:

The ornamental design for a sound absorbing cabinet for table model business machines, substantially as shown and described.
